UNITED STATES PATENT OFFICE.

GEORGE F. NILSSON, SR., OF PASADENA, CALIFORNIA.

ELEVATED AERIAL TROLLEY TRANSPORT.

Application filed April 30, 1923. Serial No. 635,432.

To all whom it may concern:

Be it known that I, GEORGE F. NILSSON, Sr., a citizen of the United States, residing at Pasadena, in the county of Los Angeles and State of California, have invented new and useful Improvements in Elevated Aerial Trolley Transport, of which the following is a specification.

My invention relates to transportation and the main object thereof is to provide an elevated aerial trolley transport which will be simple in construction, easy riding and highly efficient in operation.

My invention contemplates a single elevated rail and electric conductor; a floating aerial car anchored to said rail to float in the air slightly above said rail; a trolley mounted to travel along said rail and supply electric motive power to said car to propel the same; and means for lowering said car onto said rail at stations.

Other objects and advantages will appear hereinafter, and while I show herewith and will describe a preferred form of construction, I desire to be understood that I do not limit my invention to such preferred form, but that various changes and adaptations may be made therein without departing from the spirit of my invention as herein-after claimed.

Referring to the annexed drawings which form a part of this specification:

Fig. 1 is a fragmentary side elevation of my invention.

Fig. 2 is a fragmentary view partly in longitudinal section and partly in side elevation of the dirigible balloon which carries the floating car.

Fig. 3 is a transverse vertical section of said balloon and the upper portion of the car carried thereby taken on line 3-3 of Fig. 2.

Fig. 4 is a transverse vertical section of the rail conductor and trolley taken on line 4-4 of Fig. 1.

Fig. 5 is a fragmentary plan view of my invention without the balloon.

Fig. 6 is a plan view of the trolley.

Fig. 7 is a transverse vertical section of my invention taken on line 7-7 of Fig. 1.

Fig. 8 is an elevation of one of the hooks for suspending the car from the balloon.

Fig. 9 is a diagram of the electric circuit for operating my invention.

In the drawings 1 indicates a plurality of standards spaced at suitable distances

apart which standards rest at their bases upon the ground and carry on their upper ends a single rail 2. Each standard 1 comprises three posts spread apart at their bases and converging upwardly, there being a strap 3 around the bases of said posts, a strap 4 around said posts between their bases and upper ends, and a cap 5 crowning the tops of said posts. On top of each standard is mounted a saddle 6 in which rests the rail 2. Said rail is provided with a longitudinal groove 7 in its upper face, in which rests a bar of insulation 8, which bar is also provided with a longitudinal groove 9 in which fits a metal trolley conductor 10 which is formed with a central longitudinal groove 11. The rail 2 is also provided with longitudinal grooves 12-12 in opposite sides thereof arranged opposite each other.

Vertical electrical feeder conductors 13 extend through vertical bores 14 extending through the rail 2, through plugs 15 of insulation in the lower side of said rail and through the bar 8, and are connected at their upper ends to trolley conductor 10. Clip terminals 16 are secured on the lower ends of said feeder conductors below said rail and plugs.

A pair of lead wires 17-17 rest in grooves 18-18 in each saddle 6 and are connected to the clip terminal 16 nearest said saddle. A trolley 20 includes a frame 21, a vertical trolley wheel 22, horizontal trolley wheels 23-23, and conductor tubes 24-24 leading to the trolley wheel 22. The frame 21 is provided with a central longitudinal groove 21^a extending upwardly from the lower side thereof and with horizontal grooves 21^b-21^b extending from opposite sides respectively of the groove 24 near the lower side of the frame. The lower part of the groove 21^a fits over the upper part of the rail 2 and the trolley wheel 22 rests upon rolls on the conductor 10, which wheel is journaled in the upper part of said groove on a journal 26 which is secured at its ends in the inner ends of insulated bushings 27-27 which are fitted in and extend through the side walls 28-28 of the upper part of the frame 21. The wheel 22 is formed with a central external annular flange 29 which rests in the conductor groove 11 to prevent sidewise movement of the trolley 20. The horizontal wheels 23-23 are journaled within the horizontal grooves 21^b-21^b on bolts 30-30 which extend ver-

100
105
110

tically through the lower horizontal walls 31—31 and the horizontal walls 32—32 above said walls 31—31 of the trolley frame 21, said trolley wheels 23—23 engaging the 5 rail 2 within the grooves 12—12, thus further preventing sidewise movement of the trolley. The lower ends of the tubes 24—24 are coupled to the outer ends of the bushings 27—27 by couplings 33—33.

10 Conductors 34—34 extend through said tubes and are connected at their lower ends to the ends respectively of the journal 26; the upper ends of the tubes 24—24 to the upper part of a car 35 at the rear end of 15 said car, which car is suspended from a dirigible balloon 36 by means of hooks 37. The shanks 38 extend through the roof 39 of the car 35 and nuts 40 screw on the lower ends of said shanks against the under side of said roof. The hooks 37 engage eyes 41 at the meeting ends of bands 42, which surround the balloon casing 43, said meeting ends being riveted together as at 44. The mouth of each hook 37 is closed, 20 when engaged with eye 41, by link 45, which extends across said mouth and is secured at its end respectively to the end of the hook and to a point on the hook opposite said end, by bolts 46 and 47 respectively and 25 nuts 48 and 49, which screw on said bolts respectively.

Within the balloon casing 43 are four 30 gas containers 50, 51, 52 and 53 which extend longitudinally of the balloon, and 35 rest in a saddle 54 which is constructed so that the container 51 rests directly above and close to the container 50, while the containers 52 and 53 are spaced apart in a plane between said containers 50 40 and 51. A band 55 extends around the containers 50, 51, 52 and 53 within the casing 43 to hold said containers in their proper relations. Forwardly of the containers 51 to 53 inclusive is located a motor 45 compartment 56 which is divided off from the containers by a vertical partition 57. In the motor compartment is a floor 58 on which is secured a motor 60, the shaft 61 of which extends through the forward end of 50 the balloon casing 43 in a bearing 63 and carries on its forward outer end a propeller 63.

A traveling anchor 65 travels along the rail 2 and is connected by a chain 66 to the 55 forward end of the car 35 to prevent rising and swerving sidewise of said end of the car and the balloon 36 under the influence of the propeller 63, thus holding the front end of the car close to the rail 2.

60 The anchor 65 may be constructed similar to the trolley 20 without the conductor tubes 24—24 and the bushings 27—27 as shown in Fig. 10. The wheels 23—23 engaging the grooves 12—12 hold the anchor to the rail 65 and the anchor through the chains 66 holds

the front end of the car and balloon down to their proper relation to the rail 2; that is to say, with the car raised slightly above said rail. A chain 67 connects the trolley 20 and the rear end of the car whereby the 70 rear end of the car and balloon are held in proper relative position to the rail 2 by the trolley as the front end of the car and balloon are held as above described.

The car 35 is mounted on wheels 68. A 75 motor 70 is mounted on the under side of the car near the front end and at one side thereof. Controllers 71 and 72 are mounted on the front end of the car for controlling the balloon motor 60 and the car motor 70 80 respectively.

On the outer end of the shaft 73 of motor 70 which extends transversely of the car is secured a pinion 74 formed with an external flange 75 at its inner edge. A transverse shaft 76 is journaled in a bearing 77 depending from the under side of the car near the front end thereof at the side of the car opposite the side at which the motor 70 is located. On the outer end of the shaft 76 90 is secured a roller 78 formed with an annular external flange at its inner edge.

At suitable distances along the rail 2 are erected stations 80 which are constructed with a floor 81 over which the rail 2 extends centrally, and with a platform 82 above and at the right of said floor with a stairway 83 leading from the ground up to said platform. At opposite sides of the floor 81 just below the level of the platform 82 are 100 located L-shaped rails 84 and 85, the horizontal flanges 86—86 of said rails extending inwardly from the upper edges of the vertical flanges 87—87 of said rails. The rail 84 is supported on posts 88 of the station which also support the inner edge of the platform 82. The rail 85 is supported on posts 89 upstanding from the left edge of the floor 81.

The ends 90 and 91 of the rails 84 and 85 110 which the car 35 first approaches are curved outwardly and upwardly so that the pinion 74 and roller 78 may readily pass under the upper flanges 86—86 of said rails, even though the front end of the car may be 115 turned slightly to one side, whereby the car is lowered until the wheels 68—68 of the car roll on the station floor 81. A rack 92 is secured to the under side of the upper horizontal flange 86 of rail 84, with which 120 the pinion 74 meshes so that rotation of said pinion by the motor 70 will drive the car along the station floor until the car is stopped opposite the station platform 82, from which platform the passengers get on and off the 125 car. The vertical flanges 87—87 of tracks 84 and 85 prevent the car from shifting sidewise in the station.

The wiring of my transport is illustrated in Fig. 9. One pole of a generator 100 is 130

grounded at 101. The other pole of said generator is connectd to a main 102, which is connected at suitable intervals to the rail conductor 10 by the feeder wires 17 and conductor 13. The rail 2 is grounded between the feeder wires 17 and conductors 13 as indicated at 103.

The trolley conductors 34 lead from the trolley wheel 22 and connect to the arm of car controller 72 and to one end contact of balloon controller 71. A lead 104 connects to one end contact of car controller 72 and to one pole of car motor 70. A lead 105 connects to the other pole of car motor 70 and to one pole of balloon motor 60. A lead 106 connects to the other pole of balloon motor 60 and to the switch arm of balloon controller 71. A lead 107 connects to the trolley wheels 23-23 and to the lead 105, said 20 wheels carrying the current to the rail 2 as distinguished from the conductor 10.

Having described my invention I claim:

1. In a transport as disclosed, a rail, a floating car, a propeller for driving said car, a trolley traveling along said rail, and electrical means supplied by electricity by said trolley for rotating said propeller and driving said car adjacent said rail, stations along said rail at suitable distances apart, 25 said stations including two longitudinal side rails, a rack under one of said rails, a roller and a pinion journaled on the car for respectively engaging the under side of one of said rails and said rack on the other rail for 30 directing said car into said stations and for 35

holding said car down in said stations, and electrical means for driving said pinion to cause said car to travel through said station, said electrical means being supplied with electricity by said trolley. 40

2. In a transport as disclosed, a rail, a floating car, a propeller for driving said car, a trolley traveling along said rail, and electrical means supplied by electricity by said trolley for rotating said propeller and driving said car adjacent said rail, said rail being formed with longitudinal grooves in opposite sides, a conductor carried by said rail on top thereof, but insulated therefrom, said trolley comprising a frame, a vertical trolley wheel 50 resting upon said conductor and horizontal trolley wheels engaging said grooves. 45

3. In a transport as disclosed, a rail, a floating car, a propeller for driving said car, a trolley traveling along said rail, and electrical means supplied by electricity by said trolley for rotating said propeller and driving said car adjacent said rail, said rail being formed with longitudinal grooves in opposite sides, a conductor carried by said rail 55 on top thereof, but insulated therefrom, said trolley comprising a frame, a vertical trolley wheel resting upon said conductor and horizontal trolley wheels engaging said 60 grooves, the current being conducted from said conductor through said vertical trolley wheel and returned through said horizontal trolley wheels and said rail. 65

GEORGE F. NILSSON, Sr.
